UNITED STATES PATENT OFFICE.

FRANCIS ILLÉS, OF BUDAPEST, AUSTRIA-HUNGARY.

STOPPER FOR BOTTLES FOR AERATED WATERS OR OTHER LIQUIDS UNDER PRESSURE.

SPECIFICATION forming part of Letters Patent No. 746,841, dated December 15, 1903.

Application filed October 23, 1901. Serial No. 79,788. (No model.)

To all whom it may concern:

Be it known that I, FRANCIS ILLÉS, a subject of the Emperor of Austria-Hungary, residing at 12 Kossuth-Lajos utca, IV, in the city of Budapest, Empire of Austria-Hungary, have invented certain new and useful Improvements in Stoppers for Bottles for Aerated Waters or other Liquids Under Pressure, of which the following is a clear, true, and exact specification.

This invention is designed to take the place of the costly siphon-tops at present in use for bottles containing aerated liquids or other liquids under pressure; and it consists of an extremely cheap and hygienic stopper which can be opened merely by the pressure of the finger or thumb.

The accompanying drawings illustrate the invention, which can be fixed either in the neck of the bottle itself or in a top adjusted in the neck, applied in various ways.

Figures 1, 2, 3, 5, 6, 7, and 9 show the invention fixed in the neck of the bottle itself, and Fig. 4 shows it fixed in an independent stopper-shaped head.

Fig. 1 shows a bottle provided with the present stopper, the bottle-neck and the device being shown in section on line *z z* of Fig. 9. Fig. 2 shows a horizontal section on line *x x* of Fig. 1. Fig. 3 is a vertical section on line *y y* of the modification shown in Fig. 6. Fig. 4 is a vertical sectional view of a further modification. Fig. 5 is a vertical sectional view of yet another modification. Fig. 6 is a side view of the modification shown in Fig. 3. Fig. 7 is a side view of the modified stopper shown in Fig. 5. Fig. 8 is a detail view of the clasp or band. Fig. 9 is a side view of Fig. 1.

The invention consists of a rubber ball-valve *b*, which closes the outlet-pipe *a* at its inner end. This valve is formed on the end of a rubber sheath *c*, which is drawn onto the horizontal arm *d* of an angle or bell-crank lever *d h*, which arm passes through a lateral opening *e* in the bottle-neck, Figs. 1, 2, 3, 5, or of the bottle-stopper *g*, Fig. 4, of porcelain, glass, or other similar substance. The arm *d* is rigidly screwed into the arm *h* and forms, with the same, a bell-crank lever. This lever is either provided with a spring-tongue *i* between its inner surface and the

bottle-neck, or the arm *d* may be bent round, as shown at *i* in Figs. 3 and 5, to form the spring, and a handle, such as indicated at *h²*, 55 may be attached to the said spring, so as to form a convenient means of handling the closure, as will be readily understood. When the device is mounted in the stopper, Fig. 4, the spring *i²* is mounted between the arm *h* 60 and the stopper. The object of the spring is to hold the valve closed. The opening *e* is at the same time hermetically sealed by a rubber washer *j*, which is also mounted on the arm *d*, Fig. 1, or by a flange or collar *k* 65 on the rubber sheath *c*, which surrounds the arm *d* and is pressed up externally against the opening *e* by a clasp or band *l*, Fig. 3, encircling the bottle-neck *f* or the stopper *g*.

The clasp *l* may be secured in any desired 70 way—for instance, one end may be formed with a tongue *m* and the other with an eye *n*, Figs. 5, 7, and 8, by means of a screw or bolt *o*, Figs. 1 and 2, or a set-screw *p*, Fig. 4.

The outlet *a* is either fitted direct into the 75 bottle-neck *f*, as in Fig. 3, or into a suitably-shaped and, if desired, ornamental top *g*, Figs. 1, 5, 6, and 9, of porcelain, glass, or similar material. In the latter case the externally-grooved stopper is pressed into or 80 screwed into the internally grooved or threaded bottle-neck *f*, Figs. 1 and 3, an intermediate ring or rubber *q* being inserted.

By pressing the handle-shaped arm *h* of the cranked lever *d h* against the bottle-neck *f* 85 against the stopper *g* the valve *b* is opened.

Having now particularly described and ascertained the nature of the said invention and in what manner the same is to be performed, I declare that what I claim is—

1. In a bottle-closure, the combination of an outlet-passage in the bottle-neck, a bell-crank lever having one of its arms extending into the bottle-neck at a point in proximity to the outlet-passage of the same, a valve supported on said arm and adapted to close the said outlet, a pivotal support on the bottle-neck for the said bell-crank lever, so located that the free end of the outer arm of the latter is a short distance from the bottle-neck 90 when the valve is closed, means for hermetically closing the outlet for the bell-crank lever in the bottle-neck and means for normally holding the bell-crank lever in a posi- 100

tion to keep the said valve closed substantially as described.

2. In a bottle-closure the combination of a bell-crank lever having one arm extending 5 into the bottle-neck in proximity to the outlet-channel of the same and provided with a valve of yielding material, an opening in the said bottle-neck having an air-tight closure in which the said bell-crank lever is pivotally 10 supported, an outer arm to the said bell-crank lever extending upwardly in proximity to the bottle-neck and being of a resilient material, a handle attached to the said outer arm, the said resilient part of the outer arm 15 lying against the bottle-neck and normally holding the valve closed substantially as described.
3. In a bottle-closure the combination of a bell-crank lever having its horizontal arm ex- 20 tending through an opening in the bottle-

neck and carrying thereon a valve of yielding material adapted to close up against the outlet-opening to the bottle, a band around the bottle-neck to support said bell-crank lever pivotally in the orifice of the said bottle-neck 25 and to tightly close the said opening, the outer arm of said bell-crank lever extending upwardly outside the neck in proximity to the same, and a spring located between the neck and arm to normally hold the said 30 valve closed and means for tightening the said band around the bottle-neck in the manner and for the purpose substantially as described.

In witness whereof I have hereunto set my 35 hand in presence of two witnesses.

FRANCIS ILLÉS.
